UNITED STATES PATENT OFFICE.

KENNEDY DOUGAN, OF MINNEAPOLIS, MINNESOTA.

STEERING MECHANISM FOR DIRIGIBLE BODIES.

1,384,745.

Specification of Letters Patent. Patented July 19, 1921.

Original application filed April 21, 1910, Serial No. 556,855. Divided and this application filed August 2, 1915, Serial No. 43,196. Renewed November 22, 1919. Serial No. 339,983.

To all whom it may concern:

Be it known that I, KENNEDY DOUGAN, a citizen of the United States, residing at Minneapolis, in the county of Hennepin and State of Minnesota, have invented certain new and useful Improvements in Steering Mechanism for Dirigible Bodies; and I do hereby declare the following to be a full, clear, and exact description of the invention, such as will enable others skilled in the art to which it appertains to make and use the same.

My present invention relates to steering mechanism for torpedoes or other dirigible bodies, and the present application is filed as a division of my co-pending application, Serial No. 556,855, filed April 21, 1910, and entitled "Wireless controlled steering mechanism," on which application Patent No. 1,151,867, August 31, 1915, was granted.

The subject matter on which the present application is based is illustrated in Figures 8 and 9 of the above patent, and is described in the specification of the same.

The object of the present invention is to provide means under the control of the operator to cause the positive shifting of the rudder in opposite directions to various extents.

Referring to the drawings:

Fig. 1 is a plan view of the mechanism embodying the present invention, some parts being indicated by dotted lines and some in diagram;

Fig. 2 is a side elevation of the parts shown in Fig. 1, some parts being sectioned on the line $x^2 x^2$ of Fig. 1.

The numeral 1 indicates a framework which constitutes part of, or is carried by the torpedo or other dirigible object. The numeral 10 designates the sector gear secured to an upright spindle 11 suitably journaled in the frame 1. The numeral 14 designates a clutch lever or member secured to the upper end of the rock shaft or spindle 11 and having a segmental slot 14'. The numeral 12 indicates a crank arm which is connected by a rod 18 to the arm 16 of the rudder 15, the shaft 17 of which latter is suitably pivoted to the rear portion of the torpedo or dirigible object.

The mechanism comprises two rotary shafts 2 and 4, driven by worm or other gears 5 through shaft 6 that is continuously driven from a small motor 7. This

motor 7 may be connected to the shaft 6 in any suitable way, as through speed reducing gears 7a. The shafts 2 and 4 have ratchet wheels 8 and 8' rotatable thereon, and also rotatable on said shafts are pinions 9 that mesh with the sector gear 10, previously noted as connected to an upright rock shaft 11. The ratchet wheels 8 and 8a are connected to the respective co-operating gears 9, through gearing A which is of the arrangement disclosed and claimed in my prior Patent 1,071,895, of date, September 2nd, 1913, entitled "Governing mechanism," and which mechanism is so arranged that stopping of either ratchet wheel will start the gear on the main shaft turning in a direction to turn the gear 10 and clutch member 14.

A pawl arm 48 is fixed on a pivot spindle 49 shown as journaled on the upper end of the rock shaft 11 and in a bearing on the frame 1. This pawl arm has an extension 48'. A lever 50 has a hub 51 mounted to turn freely on the spindle 49, and in respect to the pawl arm 48. The arm 48 and lever 50 are held normally in alinement, by a tension spring 52 shown as formed as a flat zigzag connecting the end of the extension 48' to a stud 53 on lever 50. The said lever is provided with a longitudinal slot 85 which receives an eccentric pin 55 carried by a small rotary disk 56 secured to a toothed pinion 57 that is fixed on a shaft 58 journaled in the frame 1. Said pinion is driven by a gear 59 and a ratchet wheel 60, fixed on a shaft 61 journaled in frame 1. The object is to turn and stop the eccentric pin 55 at four points ninety degrees apart, by stopping ratchet 60. The proportions shown are such that each tooth of the ratchet corresponds to one-fourth revolution of the eccentric 55. But it is obvious that the ratchet teeth may be shorter so that several steps might be employed to turn the eccentric ninety degrees. In the positions 55, and 55b, Fig. 1, the eccentric holds the lever 50 and pawl arm 48 at neutral position, and in quartering positions 55c and 55d, it holds the lever 50 at an angle to one side or the other of its neutral position.

The arm 48 is a pawl arm and carries a double-acting stop pawl 26 pivoted thereto at P, and poised between the ratchet wheels 8 and 8'. This pawl 26 has a rectangular lug 26' that works in the segmental slot 14' 110

of the clutch lever 14, and it is yieldingly held in a normal intermediate position in respect to the said lever 48, by a coiled spring 26".

5 As shown, the ratchet 60 is driven by a solenoid 62, core 63, arm 64 and driving pawl 65. The circuit of the solenoid may be opened and closed by any suitable controlling mechanism, not shown. The arm 64 10 turns freely on shaft 61, and it rigidly supports the core 63, thus eliminating all unnecessary friction on the arm and core. The arm 64 is returned to normal position by a spring 66. A retaining pawl or detent 15 67 prevents backward rotation of the ratchet 60. Forward movement under momentum is prevented by a friction spring 68 or equivalent.

The purpose of making the pawl lever 20 50 separate from the pawl-arm 48 and attaching a spring 52, is to permit the action of the swinging clutch member 14 on the pawl 26 and its arm 48 when retracting the pawl. During such movement the spring 25 52 yields, permitting the pawl arm 48 to turn on pivot 49 while the lever remains stationary.

The arms 48 and 50 together constitute a lever which is, in effect, flexible. In fact, 30 the two arms may be made integral provided that one of them be made of resilient material yielding in the plane of movement thereof.

By means of the eccentric 55 the operator 35 can hold the pawl 26 at neutral position as long as may be required, the rudder angle being determined by the angle of crank 12 and the rudder remaining in any position to which it is turned through frictional means 40 such as the friction of the packing through which the shaft extends. Successive actions of the solenoid 62 will throw the pawl to right, to center, to left, to center, and so on.

The first movement required of the rudder 45 50 may require the pawl to be thrown to the left. In that case the operator sends three wave impulses. The first impulse turns the pawl to right, the second to center, and the third to left. The engagement of the pawl 55 with ratchet on right was so brief that the mechanism (which takes an appreciable time to start), was not started, hence, the rudder was not turned even slightly in the wrong direction. Supposing that further movement of the rudder in the direction last 60 moved is required, the operator leaves the key open. Repeated actions of the differential gear ensue, the pawl arm 48 being each time thrown back toward the same ratchet wheel by spring 52.

In practice, the dirigible may be provided with a suitable indicator for showing its position in its course of travel. As soon as such indicator shows that the desired course 65 is being taken, the operator closes the sole-

noid circuit once and restores the controlling pawl 26 to its neutral or central position. The above has reference in which one stroke of the pawl 65 is sufficient to turn the eccentric ninety degrees.

70

What I claim is:

1. In a torpedo or other dirigible object, the combination with a rudder, of a driving mechanism comprising two normally idle gears, means actuated by either of said gears for turning the rudder, a pawl arranged to start either of the gears, a pawl arm on which the pawl is mounted, a lever connected to the pawl arm, means for maintaining the pawl in a neutral position, an electro-magnet, means operative under the influence of the magnet to shift the pawl from neutral to operative positions or reversely.

2. In a torpedo or other dirigible object, the combination with a rudder, of a driving mechanism comprising two normally idle gears, means actuated by either of said gears for turning the rudder, a pawl arranged to start either of the gears, a pawl arm on which the pawl is mounted, a lever connected to the pawl arm, means for maintaining the pawl in a neutral position, an electro-magnet, means operative under the influence of the magnet to shift the pawl from neutral to operative positions or reversely, said means including a rotatable element operatively connected to the lever.

3. In a torpedo or other dirigible object, the combination with a rudder, of a driving mechanism adapted to turn the rudder, a starting element adapted to start said mechanism, a revolute cam actuating and controlling said starting element, and means for rotating said cam, said cam having alternate neutral and operative phases to shift said starting element from neutral to operative position, and reversely.

4. In a torpedo or other dirigible object, the combination with a rudder, of a driving mechanism adapted to turn the rudder, a starting element adapted to start said mechanism, a revolute cam actuating and controlling said starting element, and an electro-magnet for actuating said cam, the said cam or eccentric pin having alternate neutral and operative phases to shift said starting element from neutral to operative positions, and reversely.

5. In a torpedo or other dirigible object, the combination with a rudder, of means for shifting the same to various operative positions, means for controlling the shifting means including a pair of oppositely disposed ratchets, which means is rendered operative upon the arresting of the movement of either of the ratchets, a pawl disposed between the ratchets and adapted to selectively engage the same to arrest their movement, a lever yieldingly connected to the sole-

125

130

5 pawl, means tending to aline the pawl with the lever, a magnet controlled cam for shifting the position of the lever, and means controlled by the movement of the rudder shifting means to release the pawl from the ratchets to permit the alining means to operate.

6. In a torpedo or other dirigible object, 10 the combination with a rudder, of means for shifting the same to various operative positions, said means including a gear segment, two sets of oppositely disposed differential gears for moving the segment in opposite directions, normally rotating ratchets associated with said gearing and adapted to selectively render the latter operative upon the arrest of their movement, a pivoted arm

carrying a pawl which is adapted to selectively engage said ratchets, an actuating lever for said arm mounted on the pivot 20 of the latter, resilient means normally tending to aline said arm and lever, a cam for shifting said lever to such positions that when the arm is alined with the lever the pawl will be engaged with either of the 25 ratchets or disposed in intermediate position between the same, and a magnet for controlling the operation of the cam.

In testimony whereof I affix my signature in presence of two witnesses.
